UNITED STATES PATENT OFFICE.

THOMAS H. McDONALD, OF PHILADELPHIA, PENNSYLVANIA, AND EMANUEL S. BACHRACH, OF NEW YORK, N. Y.

DESIGN FOR A DISPLAY-HOOK.

SPECIFICATION forming part of Design No. 25,865, dated August 4, 1896.

Application filed March 5, 1896. Serial No. 582,002. Term of patent 7 years.

To all whom it may concern:

Be it known that we, THOMAS H. McDONALD, a resident of the city and county of Philadelphia and State of Pennsylvania, and 5 EMANUEL S. BACHRACH, of the city, county, and State of New York, citizens of the United States, have invented and produced a new and original Design for Display-Hooks, of which the following is a specification.

10 In the drawings, Figure 1 is a side, and Fig. 2 a front, elevation of the hook.

The essential feature of our invention resides in the configuration of the hook, substantially as herein shown and described.

15 The hook comprises the piece of wire 1, conformed into the semblance of an inverted S, the upper loop portion *a* being larger than the lower bill portion 3, the terminal of the loop 2 having an arm 4 extending outwardly 20 therefrom and forming a shoulder 8 at the intersection of the loop end and arm, the loop and bill portions being connected by the curved section 5, which symmetrically unites them.

From about the intersection of the loop 2 25 and section 5, including the loop 2 at a point above the shoulder 8, the hook is flattened out, as at 10, and between the pointed end 6 of the bill and its lower curve is an outwardly-extending hump 7, merging by curves into 30 said parts.

Having described our invention, we claim—

The design for a display-hook, substantially as shown and described.

Signed at the city of Philadelphia, county 35 of Philadelphia, State of Pennsylvania.

THOMAS H. McDONALD.
